UNITED STATES PATENT OFFICE.

JOSEPH HARRISON, OF TUNSTALL, STOKE-ON-TRENT, ENGLAND.

DESIGN FOR A PLATE OR SIMILAR ARTICLE.

Application filed September 7, 1926, Serial No. 18,991, and in Great Britain July 6, 1926. Term of patent 3½ years.

To all whom it may concern:

Be it known that I, JOSEPH HARRISON, a subject of the King of Great Britain and Ireland, and resident of Tunstall, Stoke-on-Trent, in the county of Stafford, England, have invented a new, original, and ornamental Design for a Plate or Similar Article, of which the following is a specification, refer-

ence being had to the accompanying drawing, forming part thereof, which drawing is a face view of a plate or similar article illustrating my new design.

I claim:

The ornamental design for a plate or similar article, as shown.

JOSEPH HARRISON.
